United States Patent Office.

GEORGE B. PHILLIPS, OF POUGHKEEPSIE, NEW YORK, ASSIGNOR TO ALEXANDER G. HUES, OF SAME PLACE.

Letters Patent No. 76,808, dated April 14, 1868.

IMPROVEMENT IN MORTISING-MACHINES.

The Schedule referred to in these Letters Patent and making part of the same.

TO ALL WHOM IT MAY CONCERN:

Be it known that I, GEORGE B. PHILLIPS, of Poughkeepsie, in the county of Dutchess, and State of New York, have invented a certain new and useful Combined Drilling, Mortising, and Tenoning-Machine, applicable also to other purposes, of which the following is a full, clear, and exact description, reference being had to the accompanying drawing forming part of this specification, and in which—

Figure 1 represents a side elevation of the machine with its parts as arranged for drilling.

Figure 2, a front elevation of the same.

Figure 3, a side view of the machine with its parts as arranged for mortising, punching, or tenoning; and Figures 4, 5, 6, and 7, views of details applicable as adjuncts for doing different descriptions of work.

Like letters indicate like parts throughout the several figures.

My invention relates to a machine which is so constructed as that it combines, in the one, the uses of several machines, by merely certain changes in or substitution of its details, and the nature of my invention consists in a detachable or hinged table-holder, connected to the standard or frame of the machine in such manner that it may be readily detached or be turned aside, and so constructed as to receive and hold in a central aperture, the shank of the table or other support adapted to the character of work to be operated on, as hereinafter described.

Referring to the accompanying drawing, A represents a bench or table, on which the frame, B, of the machine is bolted or otherwise secured. C is the drill-stock or tool-holder, constructed so as to be capable either of vertical play through, or fixed rotation in, guides or bearings a b, formed in projections or arms of the frame. When the machine is designed to be used for drilling, the stock C, not being required to have longitudinal travel downwards, the work moving up to the drill, it, the stock, is then locked or secured against such movement, and restricted to a rotary motion by an adjustable collar, D, provided with a set-screw or locking-pin, e, which, gearing the collar with the stock, restrains the latter, by the intervention of the bearing b, from any downward action.

The table or face-plate, E, on which the work to be drilled is held or secured, is constructed with a shank, d, that fits through a guide or holder, F, and is caused to carry the work up to the drill, e, (as it is rotated,) by means of a cam-shaped lever, G, working on a shaft, f, that is connected with a lower frame or bracket, H, the cam formation of said lever working against the under side or end of the shank d. A guide, h, made adjustable further in or out from the centre of the table E, answers to direct the work under the centre of the drill, or, it may be, in some cases, the mortising or punching-tool.

To rotate the drill in the required direction, the upper end of the stock is fitted with a removable bush, V, gearing with the stock by means of a feather or otherwise, and having attached to it a bevel-wheel, i, that gears with a bevel-wheel, j, attached to a horizontal shaft, k, carrying at its opposite end a spur-wheel, l, which works into a driving-pinion, m, fitted so as to freely rotate on a stud or shaft, n, secured to a slide or otherwise made adjustable up or down the frame of the machine, to facilitate different sizes of wheel and pinion being used, according to the speed or power required, which is further provided for by making the bush of the pinion m, in its fit on the shaft n, or fly or hand-wheel I, with which it may be connected, to correspond with the bore of the wheel l, so that without introducing fresh wheels, or adjusting the slide carrying the shaft n, the speed or power may be varied by slipping the pinion m on the shaft k, and the wheel l on the stud or shaft n, or, it may be, by omitting the attachment of the latter and working the shaft k direct.

For punching or mortising, the gear just described may be dispensed with, and the collar D is unlocked from the stock C, so as to admit of its descent, when a spring, J, taking the place of the removable bush V, and acting against an arm, K, fitted on to the stock, does not restrain it, the descent of the stock with its tool being effected by a treadle, L, connected by a rod, o, with the arm K, and the spring J serving to throw it up again.

To drill the holes in tires, for the passage of the bolts that secure them to the felloes of wheels, the table

E is removed from the holder F, and a tire-guide or supporter, M, (see figs. 4 and 5,) inserted by its shank p. This supporter M is provided with flanges, q, on either side, so that whether the tire be of the width between said flanges, or less width, it will always cross the centre of the shank p, as represented in fig. 5, and consequently come truly under the drill.

For punching or for gumming saws, a die-holder, N; (see figs. 6 and 7,) may be secured on to the face-plate E, and a suitable-shaped die, r, inserted therein, and appropriately-shaped punch or tool, s, in the stock C.

To adapt the machine to certain other kinds of work, it may be necessary not only to remove the table E, but also the holder F, which accordingly has given it a socketed construction, as at t, to fit a tongue projecting from the frame, whereby it may be attached or detached at pleasure. Thus, for drilling and mortising the hubs of wheels, said holder may, if necessary, be removed, and (the lever G being taken away) the hub slipped on to the shaft f of the bracket H, and centred and held to its place by adjustable cones P, which will serve to fit and centre various bores of hubs larger than the shaft f. The same arrangement will likewise answer, on removing the table and its holder F, to secure the wheels for the shaping of the tenons on the ends of the spokes.

The bracket H should have a vertically-adjustable character given it, or the shaft f be adjustable to project at different heights therefrom, as, for instance, by allowing it to fit any one of a series of holes, u, or otherwise adjustable to suit different diameters or altitudes of work.

A machine, being capable of so many variations as the one here described, will be found of great advantage in small workshops or other places, as only small and comparatively inexpensive adjuncts are necessary to convert it from one kind of machine to another, and thus the purchasing of separate machines for different work is avoided.

What I claim as my invention, and desire to secure by Letters Patent, is—

The hinged or detachable holder F, so connected to the standard or frame B, that it may be removed or turned aside at pleasure, and constructed to receive the shank of the table, or other support adapted to the work, substantially as shown and described.

G. B. PHILLIPS.
